UNITED STATES PATENT OFFICE.

RUDOLPH FINZER, OF LOUISVILLE, KENTUCKY.

TOBACCO-CADDY.

SPECIFICATION forming part of Letters Patent No. 228,182, dated June 1, 1880.

Application filed February 3, 1880.

To all whom it may concern:

Be it known that I, RUDOLPH FINZER, of Louisville, Kentucky, have invented a new and useful Improvement in Tobacco-Caddies; and I do hereby declare the following to be a full, clear, and exact description thereof, reference being had to the accompanying drawings, making part of this specification.

Figure 1 is a perspective view of a tobacco-caddy with the head removed. Fig. 2 is a vertical section of the caddy closed, taken at the line *z z*. Fig. 3 is the head of the caddy, showing a groove on the under side and a plug or length of tobacco partly inserted therein. Fig. 4 is the head of a caddy, showing a groove on the inner side containing two plugs of tobacco.

Similar letters of reference indicate corresponding parts.

The invention relates to a new improvement in boxes or caddies for packing plug-tobacco or other substances, by which irregular or extra numbers of plugs or pieces may be packed in the ordinary-sized boxes or caddies made for regular or specific quantities.

Tobacco to be shipped or stored properly must be tightly packed in compact solid packages, so as to keep out air and moisture and to prevent drying or molding, &c. It is ordinarily packed in caddies of established sizes in even layers, making a solid compact mass, which is then pressed under a screw or hydraulic press until all the air and moisture are driven from between the plugs or pieces, which become an almost solid lump. The head or lid of the caddy is then pressed in against the tobacco and lined down as nearly air-tight as practicable. These caddies are usually made in regular sizes to contain regular or fixed numbers of pounds — generally twelve-pound caddies, twenty-pound, forty-pound, or sixty-pound — so that if an irregular number of pounds or plugs are ordered they cannot be properly and

tightly packed in these regular-sized caddies, more or less unfilled space is left in the caddy, and the tobacco is liable to be injured from 45 various causes, and cannot be safely shipped or stored.

My invention consists in making a caddy with one or both heads grooved on the inner side to receive one or more plugs fitted snugly 50 in the groove, so that when the heads are pressed in the whole makes a solid compact mass with no unfilled space in the caddy, thus being able to pack one or more extra plugs or pounds in the ordinary regular-sized caddies. 55

To enable those skilled in the art to understand my invention, I will describe the best mode of carrying it into effect.

In the accompanying drawings, A represents the caddy filled with plugs of tobacco; 60 B, the head, on the under side of which is the groove C, made to receive the plug E, closely fitted. When the head B is pressed into the caddy, as shown in Fig. 2, and fastened by the linings D D, the plug E is pressed tightly 65 against the tobacco in the caddy, and the whole makes a solid compact mass.

F F represent sheets of tin-foil between the layers of tobacco.

Fig. 4 represents a head with a groove containing two plugs. Both heads of the caddy may be grooved in the same way to contain any desired number of plugs.

Having fully described my invention, what I claim, and desire to secure by Letters Patent, is —

A caddy for packing tobacco or other substances in layers superinduced one upon another, with a head or heads grooved to receive one or more extra plugs or pieces.

RUDOLPH FINZER.
